DOOR CONSTRUCTION FOR HEATERS

Earl P. Baker, Minneapolis, Minn.

Original application October 6, 1934, Serial No. 747,180. Divided and this application September 9, 1938, Serial No. 229,114

6 Claims. (Cl. 110—181)

This application is a division of my application for patent for Door construction for heating boilers filed Oct. 6, 1934 bearing Ser. 747,180 and which eventuated into Patent No. 2,132,507 dated Oct. 11, 1938.

My invention relates to heating boilers and particularly to the fire door and doorway construction therein.

In the usual small heater or boiler for homes and other establishments requiring heating plants of relatively small capacity, no special attempt has been made to provide a construction in connection with which the conventional fuel burning equipment may be conveniently and effectively incorporated. As a result, considerable difficulty is encountered in the initial installation of such equipment and in the subsequent inspection and repair thereof.

An object of my invention is to provide a simple and practical construction in heating boilers adapted to facilitate the initial installation in such boilers of fuel burning equipment and to provide for subsequent convenient accessibility to the installed equipment.

With the foregoing and other objects in view, which will appear in the following description, the invention resides in the novel combination and arrangement of parts and in the details of construction hereinafter described and claimed.

In the drawings, Fig. 1 is a fragmentary elevational view, in perspective, illustrating a form of my improved boiler construction; Fig. 2 is a perspective sectional view further illustrating the boiler construction shown in Fig. 1, the fire door and the ledge or lower member of the door casing being removed, as in practice, to admit of the ready installation of fuel burning apparatus; Fig. 3 is a perspective view in detail of the casing ledge; Fig. 4 is a vertical central sectional view of the structure shown in Fig. 1, and Fig. 5 is a vertical central sectional view of the structure shown in Fig. 2.

In the drawings, the boiler structure, fragmentarily shown, includes water-jacket plates 10, 11 surrounding a combustion chamber 12. Sheathing the outer plates 11 of the water-jacket is a covering 13 of insulating material, the same being encased in a jacket made up of panels 14 and corner strips 15.

Supporting the boiler proper is a channel iron base 16, the flanges 17, 18 thereof projecting inwardly from the upright web 19, the upper flange 17 providing a rest upon which the boiler proper stands and the lower flange 18 providing a foot-adapted to bear upon the floor.

At the front of the boiler structure, is a doorway which consists of communicating openings in the boiler proper and in the base 16. The opening in the boiler proper is provided with a door casing including a plate-like header 20 and plate-like stiles 21 which bridge the space between the inner and outer plates 10, 11 of the water-jacket, said header 20 and stiles 21 having marginal portions projecting outwardly beyond the jacket panel 14 at the front of the boiler. Intermediate the upper and lower extremities of the casing stiles 21 are U-shaped guides, one thereof, indicated by the numeral 22, being clearly shown in Fig. 2. These guides 22, horizontally disposed, open toward the front of the door casing and are adapted to receive the ends of a separate ledge plate 23. The front edges of the stiles 21, at the upper portions thereof, are inclined, as shown, said edges together with the front edge of the header 20 lying in a plane sloping forwardly and downwardly from said header. This plane also includes the front edge of the ledge plate 23 applied to the guides 22 and wherein the rear edge of the plate abuts against limit stops 24.

A self-closing, removable fire door 25 is provided for the door casing which, as will now be understood, consists of the header 20, stiles 21 and ledge plate 23. This fire door is constructed with a frame 26 angular in cross-section, said frame having a face flange 27 and a perimetrical flange 28 adapted to encompass the forwardly extending marginal portion of the door casing. Within the frame 26 of the door is a face plate 29, the same being welded at its edges, as at 30, to the inner face of the face flange 27 of said frame. Lying against the inner face of said plate 29 is a panel 31 of asbestos or other suitable heat insulating material and lying against said panel 31 is a back plate 32. The margin of the panel 31 over-reaches and seats against the outer edge of the header 20, the inclined edges of the stiles 21 and the outer edge of the ledge plate 23 in the closed position of the door 25. The back plate 32 being smaller than the panel 31 is received within the door casing as best seen in Fig. 4. Near the corners of the fire door 25, the plates 29, 32 and panel 31 are formed with registering bores for bolts 33 which secure the panel 31 and back plate 32 to the face plate 29.

The fire door hinge includes a round rod 38 extending along and welded, as at 39, to the lower side of the flange 28 at the top of the angle frame 26 and further includes an angle cleat 40 extending along the upper forward margin of the

casing header 20. The flange 41 of said cleat rests on said header 20 and is welded thereto, the other flange 43 of said cleat occupying an upstanding position and together with said first flange 41 forming a reentrant angle in which the hinge rod 38 is revolvably received, as clearly shown in Fig. 4.

It is common practice to procure a boiler from one source and oil burning or other heating equipment of one type or another from a different source, and it is frequently more or less difficult to apply the selected equipment to the selected boiler, such difficulty residing chiefly in the trouble encountered in gaining access to the fire chamber for the purpose of appropriately lining the same and/or locating therein parts of the equipment necessarily contained inside of the boiler structure.

In the use of my invention, a boiler, having the features of doorway construction, as shown in Fig. 2, may be installed without regard to the firing equipment to be selected. With the boiler installed, the workmen equipping it with fuel burning apparatus may have convenient access to the fire chamber through the relatively large doorway leading thereto, the door 25 and the ledge 23 being easily bodily removable from the door casing. After locating any bulky part of the firing apparatus within the fire chamber 12 and applying any suitable lining to said chamber such, for example, as a ceramic facing 44 (Fig. 4) and insulating sheath 45, the doorway is walled up with a suitable closure, as at 46, an opening, as at 47, such as may be desired being left in said closure, facing and sheath to receive any part of the apparatus to be projected into the fire chamber from the outside. The closure wall 46 will extend up to the plane occupied by the lower face of the casing ledge 23 and said ledge will be put in place in its guides 22 as shown in Fig. 6. The fire door 25, hung in place on its casing simply by guiding the hinge rod 38 into the angle of the cleat 40, normally remains closed by gravity, said door being readily removable from the casing by reversing the simple process of its application. Always self-closing by gravity, said door may be easily opened from without the boiler, by hand, or from within the boiler by pressure exceeding that of the outer atmosphere. Under conditions wherein suction is created within the boiler, the fire door 25 is drawn snugly against the door casing, the asbestos panel 31 effectively gasketing the door at the forward edges of the header 20, stiles 21 and ledge 23. In this connection, it is to be noted that the hinge member 38, although held against forward movement by the flange 43 of cleat 40, is free to slide rearwardly on the flange 41 of said cleat. This permissible relative movement between the hinge members allows the door to become freely seated against the edges of the door casing.

From the foregoing it will be understood that my improved boiler construction readily lends itself to convenient and effective association with such firing equipment as may be selected for use in connection therewith.

Changes in the specific form of my invention, as herein disclosed, may be made within the scope of what is claimed without departing from the spirit of my invention.

Having described my invention, what I claim as new and desire to protect by Letters Patent is:

1. In a heater having an upright doorway therein, a casing therefor, said doorway open-

ing through the casing into the combustion chamber of the heater and affording unobstructed access thereto from top to bottom of said doorway, said casing including a header member and two stile members, and upper and lower doorway closures cooperating with the upper and lower portions of said casing, a separate plate-like divider for disposition crosswise of the doorway, said divider being adapted to serve as a casing member common to said upper and lower closures, means on the casing for removably supporting said divider, said means comprising a pair of horizontally disposed guides, one on each stile, the guides being open at their outer extremities for the reception of the end portions of said divider upon its edgewise application to said guides, inner stops on the guides, the outer edges of the stiles sloping outwardly and downwardly from the header, means for hinging the upper closure at the top thereof to said header for swinging about an axis parallel with said header, said upper closure being self-closed in an inclined position bearing by gravity against the outer edges of said header and stiles and also against the outer edge of said divider in its applied position, such engagement of said closure with said divider serving to hold the latter in place in said guides and against said stops, the lower doorway closure being removable from the casing, the removal of said lower closure and of said divider and the opening of said upper doorway closure giving unobstructed access to the combustion chamber throughout the entire height of the doorway.

2. In a heater having an upright doorway therein, a casing therefor, said doorway opening through the casing into the combustion chamber of the heater and affording unobstructed access thereto from top to bottom of said doorway, said casing including a header member and two stile members, and upper and lower doorway closures cooperating with the upper and lower portions of said casing, a separate plate-like divider for disposition crosswise of the doorway, said divider being adapted to serve as a casing member common to said upper and lower closures, means on the casing for removably supporting said divider, said means comprising a pair of guides, one on each stile, each guide having an inner stop thereon, the outer edges of the stiles sloping outwardly and downwardly from the header, means for hinging the upper closure at the top thereof to said header for swinging movement relative thereto, said upper closure being self-closed in an inclined position bearing by gravity against the outer edges of said header and stiles and also against the outer edge of said divider in its applied position, such engagement of said closure with said divider serving to hold the latter in place relative to said guides and stops, the lower doorway closure being removable from the casing, the removal of said lower closure and of said divider and the opening of said upper doorway closure giving unobstructed access to the combustion chamber throughout the entire height of the doorway.

3. In a heater, a wall structure forming a combustion chamber and a base for supporting the same in an elevated position, said wall structure having a doorway therein extending downward to the bottom thereof and opening into the combustion chamber, said base having an opening therein in downward continuation of the doorway in the wall structure, a casing for said doorway including a header member and two stile mem-

bers, said doorway and said continuing opening affording unobstructed access to the combustion chamber from the top of the former to the bottom of the latter, an upper closure for the upper portion of the doorway, said closure being adapted to be opened to clear said portion of said doorway, a removable lower closure for the lower portion of said doorway and the said continuing opening in said base, a separate casing divider for disposition crosswise of the doorway between the said upper and lower portions thereof, means on the casing for removably supporting said divider, said divider serving as a lower casing member for said upper portion of said doorway and as an upper casing member for the lower portion thereof, said divider in its applied position cooperating with both of said closures, the removal of said lower closure and of said divider and the opening of said upper doorway closure giving unobstructed access to the combustion chamber throughout the entire height of the doorway.

4. In a heater having an upright doorway therein, a casing therefor, said doorway opening through the casing into the combustion chamber of the heater and affording unobstructed access thereto from top to bottom of said doorway, said casing including a header member and two stile members, and upper and lower doorway closures cooperating with the upper and lower portions of said casing, a separate plate-like divider for disposition crosswise of the doorway, said divider serving as a casing member common to said upper and lower closures, means on the casing for removably supporting said divider, said means comprising a pair of horizontally disposed guides, one on each stile, the guides

being open at the front for the reception of the end portions of said divider upon the edgewise application of the divider to said guides, said upper closure, when closed, being adapted to engage the forward edge of the divider in the applied position thereof and hold the same in said guides.

5. In a heater having an upright doorway therein, a casing therefor, said doorway opening through the casing into the combustion chamber of the heater and affording unobstructed access thereto from top to bottom of said doorway, said casing including a header member and stile members, and upper and lower doorway closures cooperating with the upper and lower portions of said casing, said upper closure being self-closing, a separate plate-like divider for disposition crosswise of the doorway, said divider serving as a casing member common to said upper and lower closures, the upper closure cooperating with the divider in the applied position thereof to hold the same in place, and means on the casing for removably supporting the divider.

6. In a heater having an upright doorway therein, a casing therefor, said doorway opening through the casing into the combustion chamber of the heater and affording unobstructed access thereto from top to bottom of said doorway, said casing including a header member and two stile members, and upper and lower doorway closures cooperating with the upper and lower portions of said casing, a separate plate-like divider for disposition crosswise of the doorway, said divider serving as a casing member common to said upper and lower closures, and means on the casing for removably supporting the divider.

EARL P. BAKER.
